UNITED STATES PATENT OFFICE.

ABEL D. TYLER, JR., OF WORCESTER, MASSACHUSETTS, ASSIGNOR OF
ONE-HALF TO SAMUEL MAWHINNEY, OF SAME PLACE.

LAST.

SPECIFICATION forming part of Letters Patent No. 601,622, dated March 29, 1898.

Application filed June 9, 1893. Serial No. 477,068. (No model.)

To all whom it may concern:

Be it known that I, ABEL D. TYLER, Jr., a citizen of the United States, residing at Worcester, in the county of Worcester and State of Massachusetts, have invented a new and useful Improvement in Lasts, of which the following is a specification, reference being had to the accompanying drawings, forming a part of the same, and in which—

10 Figure 1 represents a side elevation of a last embodying my invention. Fig. 2 is a central vertical sectional view; and Fig. 3 is a top view of the connecting-links by which the two sections of the last may be united for the purpose of relieving the hinge-joint from strain, if so desired.

15 Similar letters refer to similar parts in the different figures.

My invention relates to that class of lasts 20 which are divided transversely into two sections, so as to allow the last to be contracted in length and withdrawn from the boot or shoe without exerting any strain upon the upper by the removal of the last; and the object of 25 my invention is to increase the strength and rigidity of the last when in use and to so shape and arrange the sections of the last as to facilitate its removal and increase its efficiency.

30 The last embodying my invention is divided transversely into two sections. One of these sections A includes the heel portion of the last and the other section B the forward portion of the last, these sections being generally called, 35 respectively, the "heel" part and "fore" part. In forming these parts the last is (in the preferred form now shown) divided on the line C C', extending from the bottom of the last obliquely upward, so as to make the angle D on the portion B between the line C C' and the bottom of the last an obtuse angle. The portion B is then cut away on the line E E', beginning at or near the center of the line C C' and extending obliquely upward and 40 forward to the point E', thence on the line E' E² vertically, so as to form a right angle with the top line F of the last, forming an open space G between the portions A and B. The leaves H H of a hinge are inserted in 45 slots cut in the sections A B of the last and are held in place by pins, (shown by broken

lines H H'), so as to connect the two sections of the last by a hinge-joint having its pintle I or axis of its rotation lying within the angle included between the lines C C' and E E'. 55 The position of the pintle I is determined by making the radial distance between the axis of the pintle and the center of the heel-section at a, as indicated by the broken line a', equal to the radial distance from the axis of the pintle to the point b at the bottom of the heel-section, as indicated by the broken line b', said measurements being taken in a plane dividing the last in the center vertically, as shown by the sectional view in Fig. 2, and 60 the two equal radii a' and b' are also the radii of the arc of the circle a b, so that the path of the point b as the heel-section is raised will correspond with the arc a b, or, in other words, the axis of rotation of the heel-section 70 is concentric with the arc of the circle a b, bounding the rear side of the heel-section from the bottom of the heel at b to the center of the heel at a.

Within the heel portion A, I place a metallic bushing J to receive a bench-pin, and around the upper end of the bushing J is a metallic strap J', provided with ears J² J², lying within a slot J³ in the heel portion of the last. To the ears J², I pivot one end of a link J⁴, having its opposite end pivoted to a plug J⁵, inserted in and fastened to the front portion B of the last. The link J⁵ is provided with a lug J⁷, arranged to extend over and come in contact with the upper edge of the link J⁴ and acting as a stop, so that when the center joint of the link is depressed below a straight line, as shown in Fig. 1, the links will serve as a rigid brace to hold the two sections in their extended position. When the last is 80 in use and a strain brought upon the bottom of the last, such as would be exerted in pounding upon the sole of the boot, the links J⁴ J⁵ will hold the sections A and B together at their top and relieve the hinge from strain. 85 By separating the two sections of the last upon the line C C' and hinging them together at or near the center of the heel-section I provide an obtuse angle at D, which is not liable to catch and which provides a long surface in contact between the points C and E, and by 90 hinging the two sections together, with the

pintle of the hinge included within and near the apex of the angle C' E E', I enable the heel-section to be turned into the position shown in Fig. 2 without causing the lower corner of the heel at C to project below the line of the last when in its normal position.

The strain upon the links J⁴ J⁵ is received at one end by the strip J' and bushing J, firmly held within the heel portion of the last 10 and at the opposite end by the plug J⁶, which extends a considerable distance into the body of the last and is held by a pin J⁸.

The front portion B of the last is cut away on the line E E' sufficiently to allow the heel portion A to be raised into the position shown in Fig. 2, and an angle is formed at E' by the vertical line E' E² in order to preserve the upper portion or instep of the last at F, so as to form at this point a support for the upper.

I am aware that lasts divided transversely and having their sections hinged together are not new, and I do not claim such broadly.

The location of the pivot in or above the line of pressure between the heel and toe, tending to collapse the last, prevents the last from collapsing topward as well as bottomward. There is a tendency sometimes in the leather to contract, and thus there is a tendency to collapse the last topward, and in the course of manufacture strains are frequently exerted upon the shoe and contained last that tend to collapse the last bottomward. The described elevation of the hinge above the bottom of the last produces broad and substantial bearing-surfaces at the opposed ends of the fore part and heel part below the hinge or articulation, and these surfaces prevent the last from collapsing bottomward. By the described location of the pivotal connection a last is produced suitable for very extensive practical use without the employment of any filling-block or other device between the upper portions of the fore part and heel part.

By "line of pressure" between the toe and heel tending to collapse the last is meant all the pressures to which a last of this kind is subjected in use and which tend to collapse it. Thus in the process of manufacturing shoes these lasts are subject to longitudinal and also to vertical pressures which tend to collapse the last, and at other times the lasts are subjected to longitudinal pressures which tend to collapse them and which are exerted by the shrinkage or inherent elasticity of the upper leather after it is on the last. The line of this pressure is from about half to three-quarters of an inch above the back lower corner of the heel to the toe of the last; and when the shoe and last are in operative relation, both in as well as out of such machines, as the leveling and beating-out machines, wherein the last is subjected to enormous pressure, the line of longitudinal pressure tending to collapse the last is a fixed quantity, although the occasional vertical pressure which also tends to collapse the last may shift from point to point over the sole—

as, for instance, when the sole of the lasted shoe is subjected to the roller of such a sole-leveling machine as is set forth in the Winkley and Phillips patent, No. 540,223, of May 28, 1895; but if the sole of the lasted shoe be leveled in such a machine as is set forth in Tripp's patent, No. 296,486, of April 8, 1884, then the vertical pressure (which combines with the longitudinal pressure) will be constant. These illustrations of what is included by said phrase are not intended to be inclusive of all instances where the pressure between heel and toe tending to collapse is present or 80 occurs, and the gist of this matter will be best understood from a comparison of this last, wherein the pivot is located in or above the line of pressure between heel and toe tending to collapse the last, so that it does 85 not shut up like a jackknife, with lasts such as shown in the Smith patent, No. 395,668, of January 1, 1889, in which the hinge between the fore part and heel part is so located that it will collapse like a jackknife when a pressure occurs longitudinally of the last or vertically from bottom toward crown.

As already explained in my application, Serial No. 449,962, filed October 25, 1892, the proper location of the pivot or line of head of the hinge so as to produce a transversely divided hinged last, which, whatever its size or style, (contour,) enables the last to shorten when the heel part is turned upward and forward and also to be self-sustaining under the lengthwise pressures to which the last is subjected when in the shoe, is determined as follows: Strike three circles of equal diameter, one from the upper rear corner of the last, so as to pass through the fore part, a second from the middle point of the extreme rear line of the heel part, and a third from the lower rear corner of the heel part. These circles will intersect between the top and bottom of the last far enough above the last to insure the 105 contacting end surfaces of the heel part and fore part, the pivot being located just below the lower intersection of two of the circles if all three circles do not intersect at one point. The length of radii of the circles may be varied, but it is generally desirable in the present type of lasts to have the points of intersection rearward of the instep portion of the fore part. By reference to Fig. 2 the reason of the rule for so locating the pivot will be 115 apparent. f f represent a portion of a circle struck from the rear upper corner f' of the heel part as a center. f' f' represent a portion of a circle struck from the middle point f³ of the rear line of the heel part as a center, and f⁴ f⁴ represent a portion of a circle struck from the lower rear corner f⁵ as a center. Lines f f and f' f' intersect at f⁶ and lines f f and f' f' intersect at f⁷, the latter being the lowermost intersection. If the pivot I were 120 located at this lowermost intersection f⁷, the last would actually shorten if the heel part were moved upwardly; but the shortening would not be sufficient to allow the wider

tread and immediately adjacent side portions of the heel part to swing freely through and out of the narrower ankle-space of the shoe without distorting the latter or injuring the 5 backstays. Therefore in practice I mount the hinge in such wise as to bring its line of bend or pivot a little below this lowermost intersection.

The links J and J' may be wholly dispensed 10 with, if desired, in most uses to which lasts of this class are put, and the parts of the last may be sawed on somewhat different lines than those indicated without departure from my invention.

15 Additional advantages of my improved last are as follows: The preferable insertion of the leaves of the hinge in the body of the last gives the combined parts a strength that enables the last to withstand the heavy pressure 20 frequently exerted upon the bottom of the last by leveling and beating-out machines, there being no liability of tearing the fastenings from the wood. The location of the hinge permits the shortening of the last when 25 the heel part is swung upward and forward without scraping the lower front corner of the heel part against the insole of the shoe and thereby abrading it.

What I claim as my invention, and desire 30 to secure by Letters Patent, is—

1. A last comprising a fore part and a heel part connected by a pivot to enable said parts to have a relative movement for shortening the last, said pivot being located in or above 35 the line of pressure between the toe and heel tending to collapse said last.

2. In a transversely-divided last, the combination of a heel part and a front part divided on a line extending from the bottom to 40 the top of the last and having an angular piece removed forming a space, as at G , with 45 its apex near the center of the last, said heel and fore parts being provided with transverse slots in a horizontal plane to receive the leaves of a hinge; a hinge uniting said heel and front sections having its leaves inclosed within 50 said transverse slots in the heel and fore parts, and means for retaining said leaves within said slots, whereby the strain in a ver-

tical plane upon the leaves of the hinge, is 50 received by the body of the last, substantially as described.

3. In a transversely-divided last, the combination of a heel part and a fore part divided on the line C, C' , and having an angular piece removed, forming the sides E, E' , and E, C' , and inclosing an angle having its apex near the center of the last, said heel and fore parts being provided with transverse slots in a horizontal plane to receive the leaves 60 of a hinge; a hinge uniting said heel and fore parts and having its leaves inclosed within said transverse slots in the heel and fore parts and means for retaining said leaves within said slots, whereby the strain in a vertical 65 plane upon the leaves of the hinge is received by the body of the last, substantially as described.

4. In a transversely-divided last, the combination of a heel part A , provided with a 70 metal bushing J , a fore part B hinged to said heel part, a plug J^6 inserted in and attached to said fore part, a strap J' inclosing said bushing J and having ears J^2 and links J^4 and J^5 connecting said ears and said plug, whereby 75 said heel and fore parts are connected at the top, of the last, substantially as described.

5. In a transversely-divided last, the combination with a fore part and heel part formed with opposed contacting ends from the bottom of the last upwardly to near the middle thereof, and with an open space, above said contacting surfaces and between the upper portions of the inner ends of the fore part and heel part, of a hinge whose leaves are 80 respectively inserted and secured in the fore part and heel part with the line of bend of the hinge above said contacting surfaces, all arranged and operating, substantially as described, to permit the last to shorten when the 85 heel part is turned upward and forward, and to make the last self-sustaining under lengthwise pressure in the shoe.

Dated this 2d day of June, 1893.
